UNITED STATES PATENT OFFICE.

JOHN THOMAS WOOLSTON, OF TOWCESTER, ENGLAND, ASSIGNOR TO OSWALD VERNON FORBES, OF LONDON, ENGLAND.

BOOT AND SHOE CONSTRUCTION.

974,732.

Specification of Letters Patent.

Patented Nov. 1, 1910.

Application filed March 9, 1908. Serial No. 419,968.

To all whom it may concern:

Be it known that I, JOHN THOMAS WOOLSTON, of Towcester, in the county of Northampton, England, have invented new and useful Improvements in Boot and Shoe Constructions, of which the following is a specification.

This invention relates to that class of boot, shoe, and the like, in which a detachable and removable outer sole is employed. In certain of these forms of boots, or the like, as heretofore made, the "upper" is sewn to a "middle" sole, and this latter is chamfered or cut away around its edge, so forming, between itself and the "upper," a channel or groove into which the detachable and removable outer sole lies, when slid on to the "middle" sole. It is found in practice, however, that the said detachable sole, notwithstanding that when it is applied and secured in position by screws, is, at times, liable to be knocked off altogether, either under the direct influence of severe impact, or by creeping forward and thereby causing it to project beyond the toe of the boot, which again renders it extremely liable to be detached from the boot; this creeping having the further disadvantage of imparting an ugly appearance to the boot.

Now, the object of the present invention is to provide a boot, or the like, in which the detachable and removable sole shall, at all times, during wear, have a firm support or bearing surface, so preventing all possibility of its becoming detached, or creeping, while further preserving for the boot, or the like, its ordinary appearance. And in order that the invention may be readily understood, I will now describe it fully with reference to the accompanying drawings, wherein:

Figure 1 is a side view of the improved boot, with the detachable or removable outer sole removed therefrom. Fig. 2 is an under-side view of the same, also with the detachable sole removed therefrom. Fig. 3 is a side view with the detachable sole in position thereon. Fig. 4 is an inverted plan of the same. Fig. 5 is a transverse section taken on the line α , α , of Fig. 1, looking in the direction of the arrow. Fig. 6 is an inner face view of the detachable and removable outer sole, and, Fig. 7 is a transverse section of the same.

The same letters of reference indicate the

same parts in the several figures of the drawings.

In carrying out the invention, the boot is provided with a "middle" sole a , which is sewn, or nailed (or both) thereto, and is arranged to project, to any appropriate distance beyond and around the forward part of the "upper" b , and to form as it were a welt d , so giving to the boot great additional strength, and imparting to it the appearance of an ordinary boot, even when the detachable and removable outer sole is absent.

To the underside of the "middle" sole a , there is attached by sewing, or in any other convenient manner, a "through" sole e , of corresponding shape, but of smaller dimensions, as clearly shown in Figs. 1, 2 and 5, and having a chamfered edge e^1 . An angular channel or groove f , of suitable depth and width, is thus constituted between the "middle" sole a , and the "through" sole e , and not, as in former constructions, between the "upper" and the "middle" sole; and at the rear end of the "middle" sole, and between it and the "through" sole, a re-entering angle e^2 is formed, against which the removable sole abuts when slid into position. On to this "through" sole e , the detachable and removable outer sole g is slid, its edge then lying flush vertically with the edge of the "middle" sole a , as seen in Fig. 3, and the rim or periphery of said "middle" sole forming a support or extended bearing surface for the detachable outer sole g , and effectually preventing it from creeping when secured in place.

The construction of the detachable and removable outer sole g , used in conjunction with this improved boot, or the like, is in no wise altered or modified from that of previous constructions, that is to say, it is provided with a peripheral welt g^1 (see Figs. 6 and 7) so shaped and attached to its inner face as to form a channel g^2 , and permit it to pass readily over, or on to, the chamfered edge e^1 of the "through" sole e , and to lie within the channel or groove f , between the "middle" sole a , and the "through" sole e , when slid on to this latter sole. The said detachable outer sole may extend, as formerly, up to the waist c , of the boot, or the like; but, if found convenient, or necessary, it may be made to extend up to the middle of the waist, or up to the heel h , and be then secured in position by screws i , or rivets, the

heads of which are preferably countersunk, but any other suitable means of attachment may be employed. The detachable and removable outer sole *g*, can be made to fit flush, or form a butt joint, with the waist; or to lie under the waist, in which case it would be tongued at its inner end; or it may be arranged to lie over the waist, so forming a kind of clump sole.

10 With a boot, or the like, thus constructed, a detachable heel, or a fixed heel, may be applied, as may be required. In the drawings a detachable heel is shown by way of example in Fig. 2.

15 Having now described my invention, what I claim and desire to secure by Letters Patent is:

A boot or shoe, having in combination, a middle sole secured to the upper and projecting beyond the same to afford a welt, a through sole secured to the under face of the middle sole, said through sole corre-

sponding in shape to the middle sole but being of smaller dimensions and having its edge or periphery chamfered, a removable outer sole having a built up edge welt all the soles and the edge welt being of leather, the outer sole being slid over the through sole and its edge welt engaging over the chamfered edge of the through sole and under the projecting welt of the middle sole, the said projecting welt forming an extended bearing surface for the built up welt of the outer sole and being vertically flush therewith, and fastening means for detachably securing the outer sole to the through sole.

In witness whereof, I have hereunto signed my name in the presence of two subscribing witnesses.

JOHN THOMAS WOOLSTON.
